UNITED STATES PATENT OFFICE

BARTON H. BRINEY, OF INDIANA HARBOR, INDIANA

HEATING BOILER

Application filed April 7, 1927. Serial No. 181,768.

This invention relates to improvements upon old style cast iron heating boilers, either steam or hot water system.

The principal object is to generally improve upon structures of this class by providing one of simplicity, one which is substantial and durable, easily constructed, and otherwise efficient in construction and operation.

10 One of the specific objects of the invention is to provide a boiler which will be economical in the consumption of fuel, or in other words, capable of utilizing, to the very fullest extent, the heat produced by the combustion of the fuel, which may be either oil, gas or coal, while at the same time, not complicating the construction, and rendering it capable of easy cleaning and repairing.

15 The particular details and novel organization thereof will become more readily apparent from the following description and drawings.

In the drawings:

20 Figure 1 is a front view of the complete assembly with portions broken away to disclose internal structure.

Figure 2 is a side view, with portions broken away and shown in section.

25 Figure 3 is an enlarged fragmentary sectional and elevational view showing a special spray nozzle and mounting therefor.

Figure 4 is a view similar to Figure 3, showing a special intake water fitting, and mounting therefor.

30 Figure 5 is a cross section through one of the copper tubes.

Referring now to the drawings in detail, it will be seen that the reference character 1 designates the base which is of general rectangular configuration and which is in the form of a shell, having an appropriate interior lining 2, forming the wall of the fire box. On one side is an entrance opening 3, by means of which access is had to the interior of the fire box, for placement of the burner. Above this is a peep hole 4, to permit the interior of the fire box to be clearly observed from time to time to ascertain operating condition of the burner. On one or 50 both sides (see Figure 2) are hingedly

mounted doors 5, which operate as safety appliances, and which swing open in the event that an unusual and dangerous pressure is formed within the fire box. Seated on the base is a boiler proper generally designated by the reference character 6. This comprises a water jacket including inner and outer spaced parallel walls 7 and 8 respectively, adapted to provide the space 9 therebetween. For convenience the wall 10 is designated as the boiler head. Also the reference characters 11 are employed to designate special boxes at the bottom of the boiler. Formed on the top of the boiler at opposite sides are similar domes 12 of general elongated ovate configuration. Located between these is a smoke hood 13, which is in communication with the smoke flues 14, which are connected with the head wall 10 and the top wall. A stack pipe 15 is connected with the hood 13, for conducting the particles of smoke to the chimney. Steam mains 16 are connected with the respective steam domes 12. Also mounted on one of the steam domes is a safety valve 17, and mounted on the other one is a pressure gage 18. Then, too, a level gage 19 is provided on one side of the boiler. Connected to the opposite side of the boiler is the feed water pipe 20 and cold water return pipes 21. Particular emphasis is to be laid upon the construction of the water circulating and heating tubes, one of which is generally designated by the reference character 22. Incidentally the tube is formed of copper and is of the oval cross sectional shape indicated in Figure 5, in order to provide a greater heating surface. As is customary, the tube is formed of a plurality of bent coils, horizontally disposed. It will be noticed, however, that the adjacent coils are bent into 90 zig-zag formation, as indicated in Figure 2. The individual coils are designated by the reference characters 23.

The intake end of the lowermost coils 23 (see Figure 4) is connected with the special fitting, and anchoring element 24. This comprises a casting, having an appropriate connection 25 having a flat top 26 and a restricted intake 27. The intake 27 extends down through an opening in the adjacent wall of 100

the box 11 for communication with the water space 9. An elongated angle iron 28 is provided, and the vertical flange bears upon the box 11, while the horizontal flange bears upon the flattened top 26 of the fitting 24. The iron is bolted in place by bolts 29. Referring to the discharge end of the uppermost coil, as shown in Figure 3, it will be observed that this connects with a constricted discharge nozzle 30. The nozzle is of elongated tapered form, terminates in a bevelled end 31 and has a flattened head 32, at the opposite end. Again, an angle iron 33 is provided here to hold the nozzle in place, and the iron is secured in place by bolts 34.

It will be observed that the zigzag disposition of the circular coils in the circulating tubes provides proper clearance so as to allow the heat and fumes to pass between the tubes to the flues, without undue obstruction. The tubes are connected alternately to both sides of the water jacket, the discharge end being connected to the top of the boiler, at the same side the cold water is taken out. The next circulating tube is connected to the opposite side and returns to that side. In other words, the discharge and intake of each circulating tube is connected to the same side of the boiler, while the corresponding portions of the next or adjacent tube are connected to the opposite side of the boiler, thus providing the desired alternate arrangement. The special means comprising the angle irons for holding the fittings and nozzles in place is of exceptional importance, for when it becomes necessary to remove a damaged tube, this can be done without interfering with the adjacent tubes. The 45° angle cut on the discharge ends of the nozzles is important in that it serves to sway the steam against the side of the jacket. By doing this it produces a drier steam. The water jacket is formed from steel plates made of proper shape and electrically welded together. The arrangement of smoke flues is such as to attract the heat to the sides of the boiler, rendering the tubes on either side more efficient in operation.

It is believed that by carefully considering the detailed description in connection with the drawing, a clear understanding of the construction, assembly and operation of the invention will be had. Therefore a more lengthy description is believed unnecessary.

While the preferred embodiment of the invention has been shown and described, it is to be understood that minor changes in shape, size and arrangement of parts may be resorted to, if desired.

co I claim:

1. In a structure of the class described, a boiler embodying spaced walls forming a water containing and circulating jacket, a circulating tube of coiled formation supported in said boiler, a fitting on the intake

end of the tube communicating with the water jacket, a discharge nozzle on the discharge end of the tube also communicating with said water jacket, removable angle irons bolted to the boiler and holding said fitting and nozzle respectively, whereby to permit bodily removal of the tube, said fitting comprising a hollow cast body, having a tube connection and a flattened end cooperable with the complementary flange of the adjacent angle iron, said discharge nozzle having a bevelled extremity and also having a flattened head portion cooperable with the complementary flange of the adjacent retaining iron.

2. In a boiler structure of the class described, spaced walls defining a water circulating jacket, a circulating tube of coiled formation supported in the boiler, a tapered fitting on the intake end of the tube extending through an opening in the adjacent wall into the water circulating space of said jacket, said fitting having a flattened end portion, a removable angle iron bolted to said last-named wall and having one flange positioned for engaging the flat head of said fitting to force the tapered end portion into the water space and to hold the fitting in place, a discharge nozzle on the discharge end of the tube, extending through an opening in a complementary wall, said nozzle being of tapered design, having a beveled discharge extremity and having a flattened end portion at its opposite end, a complementary retaining iron fastened to the last-named wall to engage and hold the flattened head portion of the nozzle, whereby to provide a structure permitting bodily removal of said circulating tube, fitting, and nozzle.

In testimony whereof I affix my signature.

BARTON H. BRINEY.
